[57] CLAIM

The ornamental design for a jewelry chain, as shown and described.

DESCRIPTION

FIG. 1 is a top plan view of a jewelry chain showing my new design;

FIG. 2 is an enlarged partial showing of FIG. 1;

FIG. 3 is a side elevational view of FIG. 2;

FIG. 4 is a partial perspective sectional view, taken along the lines 4—4 of FIG. 2;

FIG. 5 is an enlarged top plan view of a second embodiment showing my new design;

FIG. 6 is a side elevational view of FIG. 5;

FIG. 7 is a top plan view of a jewelry chain showing a third embodiment of my new design;

FIG. 8 is a side elevational view of FIG. 7;

FIG. 9 is a top plan view of a fourth embodiment showing my new design;

FIG. 10 is a side elevational view of FIG. 9;

FIG. 11 is a top plan view of a jewelry chain showing a fifth embodiment of my new design;

FIG. 12 is a side elevational view of FIG. 11;

FIG. 13 is a top plan view of a jewelry chain showing a sixth embodiment of my new design;

FIG. 14 is a side elevational view of FIG. 13;

FIG. 15 is a top plan view of a jewelry chain showing a seventh embodiment of my new design;

FIG. 16 is a side elevational view of FIG. 15;

FIG. 17 is a top plan view of a jewelry chain showing an eighth embodiment of my new design;

FIG. 18 is a side elevational view of FIG. 17;

FIG. 19 is a top plan view of a ninth embodiment showing my new design; and,

FIG. 20 is a side elevational view of FIG. 19.

The opposite side views of FIGS. 1 through 3 and FIGS. 5 through 20 are identical to the side shown.
